UNITED STATES PATENT OFFICE.

EDWARD E. KLEINSCHMIDT, OF NEW YORK, N. Y., ASSIGNOR TO GEORGE M. SEELEY, OF NEW YORK, N. Y.

SYSTEM FOR AUTOMATICALLY STOPPING CARS OR TRAINS.

No. 882,695.

Specification of Letters Patent. Patented March 24, 1908.

Application filed February 8, 1906. Serial No. 300,038.

To all whom it may concern:

Be it known that I, EDWARD E. KLEINSCHMIDT, a citizen of the United States, and a resident of the borough of Manhattan, city, county, and State of New York, have invented a new and useful System for Automatically Stopping Cars or Trains, of which the following is a specification.

My invention relates to a system for automatically effecting the stoppage of a car or train should the engineer run past a danger signal.

The invention, generally stated, comprises an electromagnet placed between the rails in proximity to a signal, said magnet being referred to hereinafter as the track magnet, and a coil supported preferably from the under side of a car or the traction engine so as to be carried in proximity to the track magnet. The track magnet is included in a circuit controlled mechanically by the operation of the signal mechanism in such manner that when the signal is set at danger position said circuit will be closed to thereby energize the track magnet. When so energized should the engineer pass the danger signal the coil carried by the car will cut the magnetic field of force developed by the track magnet and an induced current will thereby be set up in said coil. This induced current is utilized to set in operation mechanism which will open the power circuit, or operate the throttle valve, or actuate the brake setting mechanism, according to the particular installation to which the system is applied.

The invention will be understood by reference to the accompanying drawings in which—

Figure 1 is a vertical section through a portion of a car showing diagrammatically the application to means for effecting the stoppage of the car or train, and the circuits; and Fig. 2 is a view to illustrate the manner of winding the car coil.

Referring to the drawings the numeral 1 designates the floor of a car. The coil in which an induced current is set up, as hereafter described, is supported in any convenient manner from the under side of the car on which the system is installed, or from the underside of the truck of the traction engine. In either case said coil is suspended in proximity to and below an axle of the truck. As a convenient means of suspension I show a bracket 2 secured to the floor 1, which

bracket carries a casing 3 inclosing a coil 4. A soft iron core 5 is supported by the casing 3, and around said core the coil 4 is wound. As shown in Fig. 2 said coil is wound in two sections, the inner section 6 is wound close to the core 5, and the outer section 7 is comparatively larger and separated from the inner section 6. The sections 6 and 7 are connected in series and their terminals lead to the electromagnet 8 of an ordinary form of relay, said relay being adapted to close a circuit to set in operation the mechanism presently to be described.

Inclosed within a casing 9 supported upon an iron bar 10 secured to the rails is an ordinary electro magnet 11, which will be hereafter referred to as the track magnet. The magnet 11 is included in a normally open circuit 12. A rod 13 is connected to a signal mechanism of any of the usual types so as to be positively operated thereby through the medium of a bell crank lever 13' when said signal is set both at danger and safety positions. Said rod is also connected to an arm of a switch 14 included in circuit 12. In the position shown the signal mechanism which operates rod 13 is assumed to be at safety position at which time the rod 13 maintains said switch open. Should the signal now be set at danger position the rod 13 will be moved by the signal mechanism to the right to close the switch 14 thus energizing the track magnet 11. The latter is set in proximity to the signal so that should the engineer fail to bring his car or train to a stop within the prescribed limits, or should he fail to see the danger signal, the train or car will be automatically stopped as soon as the car magnet 4 passes over the track magnet 11, in the following manner. The track magnet 11 will remain energized so long as the signal is at danger position by reason of the closing of its circuit switch 14 thereby developing a magnetic field of force. As the coil 4 cuts this magnetic field an induced current will be set up therein which is utilized to energize the magnet 8 of the relay. When said magnet is thus energized the attraction of the relay armature 15 closes a circuit 16 which includes a solenoid 17. The core 18 of said solenoid has projecting from its outer end a pin 18' which normally bears against one end of a lever 19 pivoted on a suitable bracket, said lever constituting one terminal of a circuit 20 which includes either or both solen-

oids 21 and 22. The core 18 is maintained in normal position by a spring 46 inclosed within a cylindrical portion 23 of the solenoid casting. Located in proximity to the outer end 5 of lever 19 is a fixed terminal 24 included in circuit 20. When the solenoid 17 is energized and the core 18 drawn inwardly the terminal lever 19 will be released and the outer end thereof brought into contact with terminal 10 24 by the action of a spring 25. The outer end of lever 19 carries a carbon contact break 26 of the usual type.

As before stated, the invention may be applied to electric, steam or other modes of traction, so as to effect the stoppage of a car or train by opening the power circuit, or by actuating the brake mechanism, or by actuating the throttle valve. For the purpose of illustration I have shown in Fig. 1 the application of the invention to means for setting the brakes and also for actuating the throttle valve, it being understood that one or both may be employed.

Should the invention be applied to a car or 25 train having an air brake system, then when solenoid 21 is energized by the closing of circuit 20 the core 28 of said solenoid will be drawn inwardly. Any convenient connection may be made between said core and the 30 valve controlling the train pipe. In Fig. 1 I have shown connected to said core a link 29 adapted to actuate a rod 30 through the medium of a bell crank lever 31. When solenoid 21 is energized, the rod 30 will be moved 35 to the right and will throw a lever 35 connected thereto upon the rod 35' as a center. Lever 35 when so moved will contact with the stem 36 of valve 37 thereby opening the latter and establishing communication from 40 train pipe 38 to the atmosphere to effect the setting of the brakes in a well known manner. When solenoid 21 is deenergized the lever 35 and the connections therefrom to core 28 are restored to normal position by a spring 39.

45 The present invention may also be utilized to effect the movement of the throttle valve in the case of steam traction so as to effect the stoppage of a train by connecting the core 32 of solenoid 22 with said valve. This 50 may be conveniently done by a link connection 33 between said core and a lever 40 to the stem of throttle valve 34. These parts are so adjusted that when solenoid 22 is energized the valve will be closed thus shutting off the steam supply.

According to a well-known law the amount 55 of current generated in a wire by cutting magnetic lines of force is directly proportional to the number of lines of force cut per second multiplied by the number of turns of wire passing through the magnetic field. In order to provide for all conditions of speed of travel I have constructed the coil 4 in the manner above described. When the car or 60 train is traveling at a slow rate of speed the

core 5 of coil 4 will become inductively energized and deenergized as it passes over the track magnet. This will cause the magnetic lines of force to cut the inner section 6 of said coil thus setting up a current which will energize magnet 8 of the relay. When traveling at a high rate of speed the time will be insufficient for the track magnet to appreciably energize the core 5 of the coil 4 but the radiating lines of force of the track magnet 11 70 under such condition will be cut by section 7 of coil 4 thus setting up a current in said section, which, as will be readily understood, will be of greater intensity the greater the rate of speed at which the coil 4 passes over the track magnet. The coil 4 is so suspended 80 as to come within the effective magnetic field of force of the track magnet.

In order to insure the closing of circuit 20 a sufficient length of time to effect the positive operation of the cores of solenoids 21 and 22 I have constructed the solenoid 17 in such manner as to retard for a given period the return movement of core 18 to normal position. As soon as coil 4 passes out of the field of the track magnet the solenoid 17 will be deenergized by the breaking of its circuit through the return movement of armature lever 15 of the relay, and if the core 18 of solenoid 17 should be permitted to instantly 90 resume its normal position then circuit 20 which controls solenoids 21 and 22 would also be broken, the impulse perhaps being insufficient to effectively energize said solenoids. The return movement of core 18 is, therefore, retarded so as to permit terminals 19 and 24 to remain in contact with each other a definite time. To effect this I have shown the core 18 as provided with a stem 42 to which is fixed any ordinary form of cup gasket 43. When the core 18 is drawn inwardly the gasket 43 collapses thus permitting the air within cylinder 23 below said gasket to escape around the edge thereof to the outer air through a slot 44 cut through the core 18. When the solenoid 17 is deenergized and the core 18 free to resume its normal position, the gasket 43 will be distended against the wall of cylinder 16 thereby preventing the admission of air from the upper side thereof to 100 said cylinder, air at such time passing into the cylinder only through a vent 45 in the end wall thereof, the size of said vent being controlled by a valve if desired. The tension of spring 46, the weight of core 18, and 105 the size of vent 45 are so proportioned relative to each other that a definite time is required for the admission of sufficient air through said vent to balance the atmospheric pressure on the upper side of gasket 43. Thus 110 the force of spring 46 is gradually expended in restoring the core 18 to its normal position, and terminals 19 and 24 will be held in contact with each other for the desired length of time. This construction of the solenoid 17 115 120 125 130

is substantially the same as that described in my application Serial No. 293,856, filed December 29, 1905.

What I claim and desire to secure by Letters Patent is:

- 5 1. A system of the character described comprising a track electromagnet, a signal, a normally open circuit for said magnet, means for closing said circuit and maintaining it closed when the signal is set at danger, a coil carried by the car or train wherein an induced current is set up by the passage thereof over said magnet when the latter is energized, said coil comprising inner and outer separated sections and means controlled by said induced current to effect the stoppage of the car or train.
- 10 2. A system of the character described comprising a track electromagnet, means to energize said magnet, a coil carried by the car or train wherein an induced current is set up by the passage thereof over said magnet when the latter is energized, said coil consisting of inner and outer separated sections, and means controlled by said induced current to effect the stoppage of the car or train.
- 15 3. A system of the character described comprising a track electromagnet, means to energize said magnet, a coil carried by the car or train wherein an induced current is set up by the passage thereof over said magnet when the latter is energized, a solenoid and a normally open controlling circuit for the same, a core for said solenoid, means controlled by said induced current to close said circuit, means actuated by the movement of said core when the solenoid is energized to effect the stoppage of the car or train, and means to retard the return movement of said core.
- 20 4. A system of the character described comprising a track electromagnet, a signal, a normally open circuit for said magnet, means for closing said circuit and maintaining it closed when the signal is set at danger, a coil carried by the car or train wherein an induced current is set up by the passage thereof over said magnet when the latter is energized, said coil comprising inner and outer separated sections, a brake mechanism, and means controlled by said induced current to actuate said brake mechanism to effect the stoppage of the car or train.
- 25 5. A system of the character described comprising a track electromagnet, a normally open controlling circuit for said magnet, a signal, means actuated by the signal mechanism to close said circuit and maintain it closed when the signal is set at danger, a coil carried by the car or train wherein an induced current is set up by the passage thereof over said magnet, said coil comprising inner and outer separated sections and means controlled by said induced current to effect the stoppage of the car or train.

6. A system of the character described comprising a track electromagnet, a normally open controlling circuit for said magnet, a signal, means actuated by the signal mechanism to close said circuit when the signal is set at danger, a coil carried by the car or train wherein an induced current is set up by the passage thereof over said magnet, said coil consisting of inner and outer separated sections, and means controlled by said induced current to effect the stoppage of the car or train.

7. A system of the character described comprising a track electromagnet, a normally open controlling circuit for said magnet, a signal, means actuated by the signal mechanism to close said circuit and maintain it closed when the signal is set at danger, a coil carried by the car or train wherein an induced current is set up by the passage thereof over said magnet, a solenoid and a normally open circuit therefor, means controlled by said induced current to close said circuit, mechanism connected to the core of said solenoid adapted to effect the stoppage of the car or train when said solenoid is energized, and means to retard the return movement of said core.

8. In a system of the character described mechanism carried by a car or train to effect the stoppage of the same, means for setting said mechanism in operation, a normally open controlling circuit for said means, a track electromagnet and means to energize the same, a coil carried by the car or train wherein an induced current is set up by the passage thereof over said magnet when the latter is energized, and means controlled by said induced current to close said circuit and maintain it closed for a predetermined time when the car or train is to be stopped.

9. In a system of the character described a solenoid and a controlling circuit therefor, a core for said solenoid, means connected to and actuated by said core to effect the stoppage of a car or train, a track electromagnet and means to energize the same, a coil carried by the car or train wherein an induced current is set up by the passage thereof over said magnet when the latter is energized, and means controlled by said induced current to close said solenoid circuit and to maintain it closed for a predetermined time when the car or train is to be stopped.

10. In a system of the character described a solenoid and a normally open controlling circuit for the same, a core for said solenoid, means connected to and actuated by the movement of said core when the solenoid is energized to effect the stoppage of the car or train, and means to maintain said solenoid energized for a predetermined time.

11. In a system of the character described mechanism carried by a car or train to effect the stoppage of the same, a controlling circuit

for said mechanism, a solenoid and a core therefor, means connected to and actuated by the movement of said core to open and close said circuit, and means to retard the return movement of said core when the solenoid is deenergized to prevent the breaking of said controlling circuit for a predetermined time.

In testimony whereof I have hereunto signed my name in the presence of two subscribing witnesses.

EDWARD F. KLEINSCHMIDT.
